UNITED STATES PATENT OFFICE.

CARLETON W. NASON, OF NEW YORK, N. Y.

DESIGN FOR A GRATE-BAR.

SPECIFICATION forming part of Design No. 26,525, dated January 12, 1897.

Application filed November 5, 1896. Serial No. 611,182. Term of patent 14 years.

To all whom it may concern:

Be it known that I, CARLETON W. NASON, a citizen of the United States, doing business in the city and county of New York, in the 5 State of New York, have invented or produced a new and original Design for a Grate-Bar, of which the following is a specification.

The accompanying drawing forms a part of this specification and is a perspective view o of my grate section or bar.

The leading feature of my design is what I term an "open center," air being allowed to rise freely through liberal apertures along the center line of the grate-bar. Further 5 features are a trunnion at each end, two sufficiently broad and deep connections along two lines each at a little distance from the center line, and a series of fingers extending transversely to those lines across the central o space and out beyond the connections on each side.

Referring to the drawing, A and B are the substantial portions of the grate-bar, which I have referred to as "connections," each side 5 of the center line. C and C are trunnions cast on the ends, respectively, of the central line, and D are the cross-bars or fingers arranged

parallel and equidistant, standing transversely to the centerline. The central spaces d d, &c., between the connections A B allow 30 air to rise between the bars D D along such line and form a conspicuous feature of my design. The spaces d' d', between the free ends of the bars D D, are in line each with a corresponding space d.

The ends of the bars D are in a straight line on one side of my grate-section, the further edge, as shown, and in a curved line on the other side, the nearest side, as shown. These features may be varied. 35

E is an arm extending down from one of the cross-bars D. It is of a taper form, as clearly shown.

What I claim is—

The design for a grate-bar substantially as 45 herein shown and described.

In testimony that I claim the invention above set forth I affix my signature in presence of two witnesses.

CARLETON W. NASON.
